LIQUID FEEDING SYSTEM FOR INTERNAL COMBUSTION ENGINES

William C. Pierce, New Canaan, Conn., assignor to Emerol Manufacturing Co., Inc., New York, N. Y., a corporation of Illinois

Application June 2, 1950, Serial No. 165,698

4 Claims. (Cl. 123—196)

1

This invention relates to liquid feeding or metering devices for internal combustion engines and more particularly to such a device which feeds liquid material such as a lubricating oil to the engine in accordance with its operating requirements.

The invention is an improvement in lubricating systems of the type shown and described in U. S. Patent No. 1,883,110, although the instant invention is intended to be employed in any liquid feeding system of the above mentioned type. As disclosed in the above patent, liquid feeding systems of this nature include a movable diaphragm which is acted upon by vacuum existing in the manifold of the internal combustion engines so as to adjust the opening of a needle valve and to control accordingly the quantity of liquid such as lubricant delivered to the combustion chambers of the engine through the valve opening. The device is arranged to thereby increase the effective size of the valve opening when the engine is running at a high speed so as to correspondingly increase the passage of liquid to the engine. Conversely, the effective valve opening is decreased when the engine is idling, and the passage of liquid being delivered is limited accordingly. Thus, the device serves to supply an amount of liquid governed by the operating conditions of the engine.

In prior mechanisms of this type, the diaphragm was integral with the valve seat, and a spring was employed for urging the diaphragm downwardly or away from the needle valve. The vacuum or suction produced by the engine would then operate to draw the diaphragm upwardly against the action of the spring so as to close the valve accordingly. It will be understood therefore that the action of the spring was to flex the diaphragm convexly in respect to its normally planar state whereas the vacuum operated to restore the diaphragm to its normal, planar shape and then flex it concavely as the vacuum increased. It will be understood of course that the terms "convexly" and "concavely" are used relatively since the diaphragm comprises a thin annular sheet of metal.

I have determined that this action which required the diaphragm to pass from a convex to a concave state produced an erratic feeding action in that the diaphragm's movement did not depend entirely upon the vacuum but was influenced by a jerking or snapping action as the diaphragm passed through its normal, planar state. It will be recognized therefore that passage of fluid was not entirely in accordance with

2

the engine's operating requirements but its flow might be suddenly decreased at certain operating conditions.

In order to remedy the above defect, I have determined that the action is far more precise and is rendered completely satisfactory by eliminating the spring which initially forces the diaphragm into convex form and, on the contrary, providing a spring which flexes the diaphragm concavely. Inasmuch as the vacuum further operates to render the diaphragm concave, the actions of both the spring and the vacuum are in the same direction, and the diaphragm always operates on one side of its normally planar state. Therefore, it is not compelled to pass through such planar state under varying conditions of operation. As a result, it has been found that liquid feeding is uniform and various economies have been noted in the consumption of such liquid. This improvement further resulted in additional operating advantages in that the spring was found to absorb shocks of backfire which were reflected in the vacuum produced and were exerted upon the diaphragm. This is of importance in prolonging the life of the apparatus and maintaining it in proper operating condition. The instant application further includes means for adjusting the spring tension so that the same devices may serve various types of engines.

The invention will be further understood from the following description and drawings in which:

Fig. 1 is a fragmentary, cross-sectional view of a liquid feeding device constructed according to the instant invention.

Fig. 2 is a fragmentary, enlarged view illustrating a modification thereof.

The device comprises a casing or housing 10 having a substantially tubular wall 11 defining a chamber 12. Essentially, the internal parts duplicate and function as the illustrated and described mechanism in application Serial No. 721,929 of Clayton B. Pierce, filed January 14, 1947, now U. S. Patent No. 2,539,924. Briefly, a circular diaphragm 13 of thin resilient metal is secured between base member 14 and flange 15 of the housing. Diaphragm 13 is connected as by nut 16 to post 17 which supports the valve seat 18. A needle valve 19 pivotally mounted to screw 20 determines the size of the opening in valve seat 18. A predetermined relationship between the valve 19 and the valve seat 18 may be effected by means of nuts 21 and 22. A coil spring 23 disposed within the hollow of nut 22 serves to maintain the parts in correct and firm relationship.

The feed spoon 24 is adapted to receive the liquid from container 25 as the liquid travels up the tube 26 in response to vacuum actuation and thereafter through stem 17 and through the valve opening. The fluid drips from spoon 24 onto pan 27 from whence it is drawn through the orifice 28 into the conduit 29 which is maintained within the internally threaded nipple 30 by the coupling 31. A ring screw 32 provided with a window provides visual communication with the chamber 12 so that the amount of liquid dripping from spoon 24 onto pan 27 may be observed. Nuts 21 and 22 serve as adjusting means and are generally actuated pursuant to the observed flow of lubricant during the operation of the engine. The other end of conduit 29 extends through a suitable opening formed in the intake manifold of the engine between the intake valves and the throttle valve of the charge forming device in the engine. The action therefore is that which was hereinabove described.

The mechanism described is more or less conventional save for the fact that a spring is omitted between the spoon 24 and ceiling of the chamber 12. I have determined that this spring should be replaced by one which is so disposed as to eliminate the erratic feed above mentioned. Accordingly, base member 14 is formed with a central depression 35 in which is disposed a coil spring 36. The upper end of such coil spring 30 embraces the head of nut 16 which is connected to the diaphragm and to post or stem 17. The effect of spring 36 is to maintain the diaphragm in a slightly elevated or concave position relative to its normal planar state. It will be recognized that the action of spring 36 is in a large measure opposed by the inherent resiliency of diaphragm 13 so that the spring does not effect a complete closure of the valve. The diaphragm and the valve opening are, however, elevated toward closing position and the vacuum produced elevates these parts still further. Accordingly, the diaphragm never is flexed to opposite positions of its normal planar state and the liquid flow is uniform and better controllable.

The depression or chamber 35 of base member 14 further provides means for adjusting the tension of spring 36 as by the modified embodiment illustrated in Fig. 2. As shown therein, a plurality of washers 37 may be placed on the floor of depression 35 so as to produce an initially greater tension of spring 36. This expedient may be used to adapt the apparatus to the specific requirements of an engine.

The illustrated and described disposition of 55

spring 36 is of particular benefit in that it absorbs shocks of back-fire which might otherwise damage or distort the diaphragm. Thus, the useful life of the apparatus is prolonged relative to prior devices which did not so dispose the spring.

What is claimed is:

1. A device for feeding liquid from a source of supply thereof to the cylinders of an internal combustion engine or the like, said device comprising a casing, valve means for regulating the flow of said liquid to said cylinders, a diaphragm of thin resilient metal transversely disposed in said casing and retained therein around its marginal edges, said diaphragm being connected to said valve means and moved by the suction created by the displacement of the pistons of said engine for automatically adjusting the opening of said valve means so as to draw said liquid through said opening into said cylinders in an amount depending upon said suction, said casing being formed with an outlet for admitting said suction into said casing and on one side of said diaphragm so as to urge it in one direction and a spring disposed on the other side of and acting against said diaphragm so as to maintain it normally flexed in the same direction as urged by said suction, said diaphragm being free of any external opposing spring force urging it in the opposite direction.

2. A device according to claim 1 and including a base member for said casing, said base member being formed with a central depression therein adapted to communicate with the source of liquid supply, said spring being disposed within said central depression.

3. A device according to claim 2 and including a nut connecting said diaphragm to said valve means and having a head disposed on the underside of said diaphragm, said spring being helical and embracing said head at the top end thereof.

4. A device according to claim 3 and including at least one washer having a central opening disposed in said depression below said helical spring and serving as a rest for the lower end of
